UNITED STATES PATENT OFFICE.

FREDERICK G. NORTON, OF WAUKEGAN, ILLINOIS.

AUTOMATIC BOOT-BLACKING MACHINE.

SPECIFICATION forming part of Letters Patent No. 496,437, dated May 2, 1893.

Application filed March 18, 1891. Serial No. 385,504. (No model.)

To all whom it may concern:

Be it known that I, FREDERICK G. NORTON, a citizen of the United States, residing at Waukegan, in the county of Lake and State 5 of Illinois, have invented new and useful Improvements in Automatic Boot-Blacking Machines, of which the following is a specification.

This invention relates to the construction 10 of automatic boot blacking machines.

My object therein has been the production of a simple and efficient machine of this class, in which a series of rotating brushes is given a movement around the foot during which 15 they may both apply the blacking and polish the shoe. In order to obtain this movement around the foot, the brushes which act upon the sides and back of the shoe are mounted upon vertical axes in swinging arms which 20 are pressed toward each other with a yielding pressure by springs, while the brush which acts upon the toe portion of the shoe is so mounted and operated that it will move from side to side over the front of the foot and rise 25 and fall according to the height of the shoe, thus adapting itself to the contour of the front portion of the shoe. The series of brushes are all mounted upon a carriage which when the motor of the machine is set in motion ad- 30 vances sufficiently to carry the brushes to and around the foot in their prescribed paths and then retreats to its starting position. The machine is also so organized as to feed the brushes with blacking during their advance 35 movement and to shut it off during their retreat, thus leaving them at liberty to polish during the latter movement.

The details of construction, as well as the novel features of the machine will be fully 40 understood from the description which I give below when considered in connection with the accompanying drawings, wherein

Figure 1 is a plan of my machine, the top of the surrounding case being removed. Fig. 45 2 is a side elevation; the side of the case being omitted. Fig. 3 is an enlarged partial horizontal section on substantially the plane of shaft G in Fig. 2. Fig. 4 is a detail section showing the mechanism for supporting and 50 actuating the toe brush. Fig. 5 is a plan of the parts shown at Fig. 4. Fig. 6 is an elevation of one of the swinging arms carrying the

side brushes. Fig. 7 shows the rack for reciprocating the carriage carrying the brushes. Fig. 8 is an enlarged detail of the cam for 55 opening the blacking reservoir valve of the toe brush. Fig. 9 is a detail of the arm actuated by the cam of Fig. 8. Fig. 10 is a detail section of the devices for actuating the valve controlling the supply of blacking to the side 60 brushes. Fig. 11 is an elevation, partly in section, of one of the blacking reservoirs. Fig. 12 is a section on the line 12-12 of Fig. 11. Fig. 13 is a section on the line 13-13 of Fig. 4.

In the drawings A represents a suitable base upon which the machine is mounted.

a a represent raised platforms or foot rests on which the feet may be placed while the shoes are being blacked.

B represents a suitable casing covering the operative parts of the machine when at rest. This covering is open at the end toward the rests a, and the mechanism moves out of such open end when the motor is set in motion, as 75 hereinafter explained.

I have shown in the drawings a machine adapted to black both shoes at the same time, but it will be understood that instead of this the machine may embody only one set of 80 brushes, and repeat its operation.

All the moving parts of the machine are mounted upon a carriage consisting of a cross beam C, and branches c. At D is the electric motor by which the machine is operated, d 85 being the binding posts for the electrical connections.

The particular description of motor employed with the machine is entirely immaterial, and hence I do not enter into any detail of explanation with regard to it. It actuates a pinion E, and through such pinion gives motion to the machine. This pinion meshes with a gear e mounted upon a shaft F carrying a miter pinion f meshing with a like pinion g upon the cross shaft G supported from the beam C. From this shaft G the various brushes are actuated as hereinafter more fully set forth. Shaft F also carries a worm H meshing with a worm gear h mounted upon a vertical shaft i, the latter carrying a pinion j meshing with a rack J, stationary as regards longitudinal movement, but movable laterally, as stated farther on. Surrounding the

rack J is a frame K, united to the rack so as to be rigid therewith, by cross bars k supported upon the plate A. The rack and surrounding frame are also fast upon a cross shaft L which has freedom to slide in its bearings m. By means of this pinion j, in conjunction with the rack and the frame, the carriage C c is reciprocated forward and back at each blacking operation, the carriage being supported upon rollers M at each end of the cross beam and the roller N at the rear, track bars n being provided for each of said rollers. It will be readily seen that when the motor is set in motion that a rotary movement will be imparted to pinion j, and as the rack is held by its shaft L against any longitudinal movement, the resultant effect is necessarily a longitudinal movement of the main carriage. This movement which advances the brushes to their work continues until the pinion j reaches the end of the rack, at which time being in continuous motion and confined by the frame K, said pinion forces the rack laterally and then commences to engage the teeth upon the opposite side of the rack and to cause a retreat of the carriage. This retreat continues until the pinion has reached the other end of the rack, when it moves around that end and forces the rack back to its starting position ready for another advance.

For operating upon the sides and heel of the shoe I provide a pair of brushes O O, one at either side of the foot and mount them upon spring pressed swinging arms P. Each of said brushes is mounted upon a vertical shaft o in the end of said swinging arm, and said shaft is actuated by the miter gears q, the shaft p extending longitudinally of the arm P, the bevel pinion r meshing with the gear R upon a vertical journal S, and the gear s upon the main cross shaft G. Each arm P finds support in a bracket T and is forked at the end joined to the bracket, so as to give room to the gears R r, and is pivoted at each junction of the fork with the bracket, the journal S forming one pivot and the other pivot being indicated at t (Fig. 6). The arms P are employed in pairs, one for supporting a brush at each side of the foot, and are yieldingly pressed toward each other at their operating ends by springs W, secured to the cross bar C and extending forward and acting upon the arms near the brushes. Each of the brushes O carries a blacking reservoir 3, and the flow of the blacking from these reservoirs is controlled by appropriate valves 4, (Figs. 11 and 12) seated in cylinders 5 provided with discharge openings 6 adapted to be closed by rotating the valve.

A simple construction of the valves and cylinders is illustrated, the former being cut away at one side and the latter being open upon the side adjoining the reservoir. These valves are opened momentarily and immediately closed again during the forward movement of the brushes by any suitable mechanism, such for instance as the following: Each

valve has a stem 7 and a crank arm 8, and the latter is joined by a pitman rod 9 to a pivoted lever 10 stationarily supported from frame C by a bracket 11. A spring 10^a (Fig. 10) draws the lever 10 in the direction indicated, and by so doing retains the valve in its closed or normal position. Said spring is however overpowered during the forward movement of the carriage by the contact of a depending elbow extension 12, rigid with lever 10 and preferably carrying an anti-friction roller 13, with a stationary stop 14. This contact results in a tipping of the elbow and the lever, so that the roller 13 may ride over the stop and also in a partial rotation of the valve sufficient to discharge a small quantity of the blacking. The stop 14 upon its farther side may be inclined as shown, or it may be prolonged to any extent desirable to insure the discharge of a sufficient quantity of the blacking, but I prefer that the valve should be retained in the open position only an instant and to employ a plurality of stops 14 in order to repeat the operation just described at a later stage in the advance of the carriage and thus supply the brushes at intervals instead of once for all. In this manner the blacking is economized and is more evenly distributed upon the shoe than it would be if the valves were opened but once. The stop or stops 14 are secured to a stationary bar 15 attached to base A. And where more than one stop is employed, it will be understood that spring 10^a closes the valve between the contacts of the elbow with the several stops. During the retreat of the carriage, there is no actuation of the reservoir valves because the foot x in which the roller 13 is mounted, is pivoted in a recess y in the elbow 12, which recess allows such foot to yield and ride over the stops 14 when the carriage is moving back, while it holds the foot rigidly during the advance movement.

The toe brush is indicated at 16. It is supported upon a horizontal axis 17, carrying bevel gear 18 engaging with a like gear 19 upon the vertical shaft 20 furnished with a bevel gear 21 (Fig. 4) meshing with a like gear 22 upon the main cross shaft. Through this train of gearing the brush receives its rotation. It is also vibrated laterally over the shoe by appropriate mechanism and the means I have employed for this purpose I will now describe. The brush arbor 17 is supported in an arm 23 which encircles and swings upon the shaft 20, said shaft 20 being supported in a frame 24 which is journaled upon the main shaft G. In this frame 24 is also journaled a short shaft 25 carrying a gear wheel 26 receiving power from the shaft 20 through the pinion 27. Upon its upper end shaft 25 carries a crank and wrist pin 28 and 29, such wrist pin working in the slot 30 of a horizontal arm or extension 31 of the arm 23. By this mechanism the brush is during the operation of the machine vibrated to and fro over the toe of the shoe, as will be readily

understood. The vibrating movement thus given the toe brush is not in a horizontal plane but is a rising and falling movement in order that the brush may conform to the foot and properly black the sides as well as the top of the toe portion and to permit this compound movement, the brush and its supports and frame 24 are made capable of swinging upon the main shaft G as a center, and the shoe itself is made the means of both causing and determining the extent of the rise and fall. A spring 33 is placed between the frame 24 and the cross beam C, the power of which is exerted in an upward direction and thus tends to throw said frame and the parts supported thereby including the brush over toward the shoe, the spring and brush being located at opposite sides of the main shaft G upon which the structure swings. With this construction, it will be obvious that the brush will in the vibrating movement ride over the shoe, moving in irregular curved lines corresponding to the outline of the shoe, and remaining in operative contact with the surface thereof during the entire operation. The features just described also permit the vibrating movements to vary according to the height or width of the portion of the shoe being blacked or polished. An arm and set screw 34 and 35 may be employed to limit the downward movement of the brush, its upward movement being limited only by the possible compression of the spring 33. A stud 36 is preferably employed to hold the spring in place, and this stud may be integral with shaft 25.

The toe brush is provided with a blacking reservoir 37 similar to those used with the side brushes and controlled by a similar valve 38. This valve is also opened during the advance of the machine by appropriate devices, which may be the following: The stem of valve 38 carries a laterally and downward extending arm 39 which is actuated by an arm 40 upon the upper end of a shaft 41 supported from frame 24 in bearings 42 and 43. The normal position of arm 40 is indicated by full lines and its actuating position by broken lines Fig. 5. The lower end of shaft 41 carries an arm 44 on which is pivotally mounted a dog 45 carrying a pin 46, and the latter contacts with a stationary cam 47 as the machine advances to its work. The dog 45 has a side extension 48 which engages with a stop 49 upon the arm 44, and a spring 50, shown by broken lines Fig. 9, maintains the dog normally in the position given at said figure. This construction insures a deflection of arm 44, and a consequent actuation of shaft 41 and contact at each vibratory movement of the brush arm 40 with arm 39, and an opening rotation of valve 38 these movements taking place whenever the carriage advances and brings pin 46 against the cam 47. No such result is caused during the return movement however because the pivoted dog can then yield and allow the pin to ride over the cam

without communicating movement to arm 44. After each actuation of the valve in this manner, a spring 51 located upon its stem closes it. Contact between arms 40 and 39 takes place only during the time arm 40 occupies its position indicated by dotted lines at Fig. 5, but there may be more than one actuation of the valve as such contact should occur at each vibration, and there may be a series of vibrations during the time the cam 47 is holding the arm 40 in its acting position, the motion of the carriage being a slow one to give the brushes ample time to do their work. In the case of the double machine shown, the valves of the two toe brush reservoirs may be connected together, and be operated simultaneously by a single cam, and I have so shown them, the connections consisting of the rod 52 and the cranks 53 and 54 affixed one to each shaft 41. The valves of all the side brushes may all be operated from a single crank shaft 55 extended across the machine and connected to all the valves and to the actuating mechanism as illustrated, and this shaft may carry a spring 56 intended to aid in closing the valves.

The operation of the machine may be briefly described as follows: The person whose shoes are to be blacked positioning his feet upon the pedestals or rests a, and the motor being set in operation the entire machine advances with a slow motion and simultaneously all the brushes begin to rotate. The side brushes move along the sides of the shoe and a little later the toe brush also begins to operate upon the shoe upper. The side brushes are supplied with blacking each time the elbow 12 encounters the stops 14, the valves of their reservoirs being opened by such contact between the elbow and stops. The toe brush is also supplied with blacking whenever the pin 46 encounters the cam 47, and it moves over the rounded face of the front portion of the shoe with a vibrating movement caused by the wrist pin of crank 28 working in slot of the horizontal extension 31. The forward movement of the carriage due to the engagement of pinion j with rack J continues until said pinion has traversed the length of said rack and then begins a return movement, the rack shifting laterally as the pinion passes around its end and the return movement commencing with the engagement by the pinion of the teeth upon the farther side of the rack. During the return movement no blacking is fed, owing to the peculiarities of construction already pointed out, but the brushes continue to rotate and are thus permitted to polish the blacking applied during the advance movement. When the carriage has reached its normal or starting position the motor is stopped and the operation is supposed to be completed. The foot rests or platforms a are rendered easy of access by persons using the machine by reason of the fact that the blacking mechanism is away from such platforms at the times when the users are getting on

and off the machine. There is no necessity therefore for the exercise of care in positioning oneself on the machine, nor is there any necessity for inserting the foot in a hole as in some constructions which have heretofore been employed. The surrounding casing covers the mechanism when not in use and protects it from injury.

I claim—

- 10 1. In a shoe blacking machine the combination of rotating side brushes mounted upon yielding arms and moving along the side of the shoe, and a rotating toe brush vibrating laterally and having liberty to rise and fall to accommodate the contour of the shoe, substantially as specified.
- 15 2. In a shoe blacking machine the combination of rotating side brushes mounted upon yielding arms and moving along the side of the shoe, and a rotating toe brush vibrating laterally and having liberty to rise and fall to accommodate the contour of the shoe, with means for automatically moving said brushes into operative contact with the shoe, comprising the rack J and pinion j, one of said parts being connected with a motor and the other with the supports of the brushes, substantially as set forth.
- 20 3. In a shoe blacking machine the combination of rotating side brushes mounted upon yielding arms and moving along the side of the shoe, and a rotating toe brush vibrating laterally and having liberty to rise and fall to accommodate the contour of the shoe, with a carriage upon which said brushes are mounted and whereby they are moved into operative contact with the shoe, substantially as set forth.
- 25 4. In a shoe blacking machine the combination of a rotating toe brush vibrating laterally and having liberty to rise and fall to accommodate the contour of the shoe, with a carriage upon which said brush is mounted and whereby it is moved into operative contact with the shoe, and a suitable motor, substantially as specified.
- 30 5. In a shoe blacking machine the combination of rotating side brushes mounted upon yielding arms and moving along the side of the shoe, and a rotating brush vibrating laterally and having liberty to rise and fall to accommodate the contour of the shoe, with a carriage upon which said brushes are mounted and whereby they are moved into operative contact with the shoe, and a suitable motor also mounted upon the carriage, substantially as set forth.
- 35 6. In a shoe blacking machine the combination of rotating side brushes mounted upon yielding arms and moving along the side of the shoe, and a rotating brush vibrating laterally and having liberty to rise and fall to accommodate the contour of the shoe, with a carriage upon which said brushes are mounted and whereby they are moved into operative contact with the shoe, and a suitable motor also mounted upon the carriage, and serving

both to move the carriage and actuate the brushes, substantially as set forth.

7. In a shoe blacking machine the combination of a suitable foot rest, a carriage movable toward and from the same, guides for said carriage, rotary brushes mounted on the carriage, actuating mechanism for rotating the brushes, a motor for moving the carriage, and connections between said motor and the brush rotating mechanism, substantially as set forth.

8. In a shoe blacking machine the combination with a series of brushes and a carriage upon which they are mounted and whereby they are moved into operative position, of a stationary rack, gearing on the carriage engaging the rack, and a motor also mounted upon said carriage and serving both to operate said gearing and to actuate the brushes, substantially as set forth.

9. In a shoe blacking machine the combination of a series of rotating brushes movable along the shoe, blacking reservoirs and their valves, and means for opening said valves comprising a stationary cam 14, foot x, and extension 12 connected with the valve, said means being arranged to operate during the advance of the brushes, substantially as set forth.

10. In a shoe blacking machine the combination of a series of rotating brushes movable along the shoe, blacking reservoirs and their valves means for opening said valves arranged to operate only during the advance of the brushes, and devices for maintaining the closure of said valves during the retreat of the brushes substantially as set forth.

11. In a shoe blacking machine, the combination of a series of rotating brushes movable along the shoe, blacking reservoirs and their oscillatory valves and means for opening said valves arranged to operate at intervals during the advance of the brushes, comprising a lever arm, and stationary projections substantially as set forth.

12. In a shoe blacking machine a rotating toe brush, mounted to yield vertically to accommodate the rounded top of the shoe and also having a vibrating movement across the shoe, in combination with a longitudinally reciprocating carriage carrying the brush supporting devices means for imparting the rotary and the vibratory movements, substantially as set forth.

13. In a shoe blacking machine, an automatic shoe blacking mechanism adapted to move forward and black the shoe and then retreat therefrom, and a platform such as a located in front of and within the limit of travel of said mechanism and adapted to support the foot during the blacking operation, substantially as set forth.

14. In a shoe blacking machine a casing open at one side, an automatic shoe blacking mechanism located in said casing and adapted to move forward through the open side to its work, and a platform for the foot located op-

posite said open side, substantially as set forth.

15. In a shoe blacking machine wherein the blacking devices are movable along the shoe, the combination with a blacking reservoir and its valve, of a stationary cam and mechanism actuated by said cam for opening the

valve at the required point in the movement of the blacking mechanism, substantially as set forth.
